UNITED STATES PATENT OFFICE.

WILLIAM TRESSELT, OF NEW YORK, N. Y.

SASH-LOCK.

1,097,379.

Specification of Letters Patent.

Patented May 19, 1914.

Application filed October 24, 1913. Serial No. 797,005.

To all whom it may concern:

Be it known that I, WILLIAM TRESSELT, a citizen of the United States, residing in the city of New York, borough of Manhattan, in the county and State of New York, have invented a certain new and useful Improvement in Sash-Locks, of which the following is a specification.

The invention relates to fasteners applied on the meeting-rails of window sashes to lock the latter, and the primary object of 10 the invention is to provide such fastener with a key-operated locking means by which the sashes may be securely fastened until 15 released by a key.

Another important object is to provide a construction in which the fastener members are secured to their respective meeting-rails by means which are concealed and inaccessible when the fastener is locked, and generally, to provide a sash lock which shall hold 20 reliably, lock automatically, and be easily applied and operated.

The invention consists in certain novel 25 features of construction and arrangement by which the above objects are attained, to be hereinafter described.

The accompanying drawings form a part 30 of this specification and show an approved form of the invention.

Figure 1 is a plan view of the sash lock in position on the meeting-rails, in the engaged and locked condition. Fig. 2 is a similar view showing the parts unlocked. Fig. 3 is a side view corresponding to Fig. 1. Fig. 4 is a front elevation of the same. Fig. 5 is a vertical section taken on the line 5—5 in Fig. 1. Fig. 6 is a vertical section through a portion, on the line 6—6 in Fig. 40. Fig. 7 is a horizontal section through the locking device alone, taken on an irregular line. Fig. 8 is an elevation of the lock cylinder.

Similar letters of reference indicate the 45 same parts in all the figures.

A and B are the meeting-rails of the upper and lower sashes respectively. On the rail A is a short strip or bar C fastened by screws C¹ extending downwardly there- 50 through into the rail, and covered by a similar bar or cover-plate C² hinged to the bar at C³. The cover carries a hook C⁴ adapted to be engaged by a portion on the movable member of the sash fastener. On the side 55 opposite to the hinge C³ is a spring-catch C⁵ fastened to the bar beneath the rear face

of the latter, and having a beveled nose C⁶ adapted to engage and hold the rear edge of the cover C² against lifting until released. Thus constructed the screws holding the hook to the meeting-rail cannot be removed while the hook C⁴ is in engagement with the other member of the sash lock.

On the rail B is a plate D having a broad base D¹ and a circular cavity in its upper face in which is received the locking cylinder E held in place by the vertical rivet D² on which it may be rotated horizontally. The cylinder carries a semi-circular flange or cam E¹ having an upwardly inclined or 70 spiral edge E² adapted to engage beneath the hook C⁴ when the cylinder is partially rotated in one direction and draw the meeting-rails together and hold them fastened, and when rotated in the reverse direction to withdraw from engagement with the hook and release the sashes. A thumb-piece E³ is provided for facilitating the movement, and a pin D³ set in the plate D serves as a 75 stop to limit the movement in each direction to about a half revolution. A semicircular slot e in the cylinder affords access to a screw D⁴ extending through the bottom of the plate D into the rail B, when the cylinder is rotated to disengage the flange E¹, 80 and when the cylinder is in the locked condition the screw is concealed beneath the closed portion of the cylinder and is inaccessible. This screw D⁴ and the screws D⁵ extending through the base D¹, hold the 85 plate and its cylinder to the rail.

The locking means for holding the flange and hook in engagement is of the well-known Yale type. A channel d in the front portion of the plate D receives a key F, indicated in dotted lines in Fig. 7, having the usual swells in its edge adapted to act upon movable pins extending into the channel or key-way. Three pins G are shown, arranged 90 parallel with each other and extending horizontally across the curved line of the joint between the cylinder E and the cavity in which it is mounted on the plate D. The pins are cut transversely to match such joint, the cut being curved to correspond to 95 the curve of the joint, and each pin is urged toward the key-way by its spring G¹ in the cylinder.

To permit free rotation the pins are arranged out of line on the circumference of 105 the cylinder, one above the other, as shown in Fig. 8, so that the portion of each pin

which travels with the cylinder will find its own mate in the plate D without interference with either of the others. The key-way d is correspondingly inclined, as indicated in dotted lines in Fig. 4. The key-way is formed partly in the body of the plate D and partly in a removable cap H secured to the plate by concealing screws H^1 extending from the lower face of the plate 10 upwardly into the cap. By the removal of the latter access is had to the pins G, and the construction also permits the holes for the pins to be conveniently drilled from the exterior of the plate.

15 When the cylinder is rotated to the locked position the pins G are automatically thrust forward across the joint, and the cylinder securely held with its flange E^1 engaged beneath the hook C^2 until the key is inserted 20 and the pins forced inwardly thereby to bring their cuts into coincidence with the joint. The cylinder may then be rotated in the reverse direction to release the flange from the hook.

25 While in the locked condition the screws C^1 are inaccessible and cannot be removed, and the screw D^4 holding the plate D to its rail is concealed beneath the cylinder E. Thus conditioned the sashes are effectually 30 locked together and held until the insertion of the key releases the mechanism.

Any number of pins may be employed arranged in a variety of ways and of varying lengths to insure against unauthorized 35 opening, as will be understood, or one pin alone may be used in less expensive forms of the invention; or other types of locking mechanism may be employed. The bar C and its cover C^2 may be in a single piece 40 with the hinge and catch omitted, and secured to the rail as usual, and the plate D secured to its rail by screws extending through the base, with the concealed screw D^4 omitted. The complete form shown is 45 preferred.

Other modifications may be made in the

forms and proportions without departing from the invention.

I claim:—

1. In a sash lock, a bar, screws adapted to 50 extend downwardly therethrough into a meeting-rail, a cover hinged to said bar and concealing said screws, a hook on said cover, a plate adapted to be secured to the other meeting-rail, and a movable member on said 55 plate, adapted to engage said hook and hold said cover against lifting and exposing said screws.

2. In a sash lock, a bar, screws adapted to 60 extend downwardly therethrough into a meeting-rail, a cover hinged to said bar and concealing said screws, a hook on said cover, a plate adapted to be secured to the other meeting-rail, a movable member on said 65 plate, adapted to engage said hook and hold said cover against lifting and exposing said screws, and a movable catch engaged with said cover.

3. In a sash lock, a plate adapted to be secured to one of a pair of meeting-rails and 70 having a circular recess, a cylinder rotatably mounted in said recess, an inclined key-way in said plate, a plurality of spring-actuated pins arranged at different levels corresponding to the inclination of such key-way, said pins extending from said key-way into said cylinder and adapted to lock 75 said cylinder to said plate, and cut transversely to match to the joint between said cylinder and plate when presented thereto by 80 the action of a key inserted in said key-way, and means adapted to be secured to the other meeting-rail and engage said cylinder when the latter is in the locked position.

In testimony that I claim the invention 85 above set forth I affix my signature, in presence of two witnesses.

WILLIAM TRESSELT.
